UNITED STATES PATENT OFFICE.

JULIUS A. MAHR, OF MINNEAPOLIS, MINNESOTA, ASSIGNOR TO COZY BABY CARRIAGE COMPANY, OF MINNEAPOLIS, MINNESOTA, A CORPORATION OF MINNESOTA.

FOLDING BABY CARRIAGE.

Application filed October 2, 1922. Serial No. 591,766.

My present invention relates to folding baby carriages of the type disclosed and broadly claimed in my four U. S. Letters Patents #1,335,122 entitled "Folding baby carriage," issued March 30, 1920, #1,363,667 entitled "Baby-carrying basket", issued December 28, 1920, 1,432,114, entitled "Folding baby carriage", issued October 17, 1922, and 1,470,630, entitled "Supplemental cover for baby carriage hoods", issued October 16, 1923, and said invention has for its object to improve the same in the several particulars hereinafter noted.

While the improved folding baby carriage can be used as a full sized baby carriage, it is well adapted for use as a folding doll's carriage.

To the above end, generally stated, the invention consists of the novel devices and combinations of devices hereinafter described and defined in the claim.

In the accompanying drawings, which illustrate the invention, like characters indicate like parts throughout the several views.

Referring to the drawings:

Fig. 1 is a right side elevation of the improved folding baby carriage with some parts sectioned;

Fig. 2 is a bottom plan view of the running gear folded;

Fig. 3 is a detail view, on an enlarged scale, of the front coupling, with some parts broken away and sectioned, and fragmentary portions of the connected post, reach and radius rods, said parts being folded as shown in Fig. 2; and

Fig. 4 is a detail view, with some parts sectioned, of the front left-hand wheel, stub axle and fragmentary portions of the connected radius rod and cross tie-bar, said parts being folded as illustrated in Fig. 2.

The folding running gear of the improved baby carriage includes a reach 5, a pair of posts 6, a pair of couplings 7, two pairs of radius rods 8, the outer ends of each pair being bent outward into axial alignment to afford stub axles 9 on which are journaled wheels 10. The couplings 7 are pivoted, one to each end of the reach 5, for longitudinal outward and downward swinging movement, in respect to the reach, and the lower ends of the posts 6 are pivoted to said couplings for like movements. These couplings 7 are in the form of saddles which rest upon the

reach 5 and posts 6 and limit the swinging movement of the posts 6 toward each other when in upright positions, as shown in Fig. 1, and normally hold said posts in diverging relation. Said couplings 7 are so arranged that the posts 6 can be folded under the running gear in substantially parallel arrangement with one another and the reach 5, as shown in Fig. 2, and are secured in this position by a buckle-equipped strap 11 permanently attached to the reach 5.

Formed with each coupling 7 is a pair of diverging downwardly and inwardly inclined sockets 12 in which the upper ends of the radius rods 8 are seated and rigidly secured by pins or rivets 13. Each pair of radius rods 8 is rigidly connected at its outer ends by a flat cross tie-bar 14 which is substantially aligned with the respective stub axles 9. When the running gear is folded, as shown in Fig. 2, the pairs of wheels 10 overlap and the cross tie-bars 14 are transversely between the reach 5 and the posts 6, and thereby hold said wheels folded. The wheels 10 are held on the stub axles 9 by cotter pins 15, and the outer ends of the hubs of said wheels and stub axles 9 are covered by caps 16 secured to certain of the spokes of the wheels. The upper ends of the posts 6 are forked to afford a pair of prongs 17, to each pair of which is rigidly secured a transverse handle 18. Formed in the upper ends of the posts 6 between the prongs 17 are outturned hooks 19 for a purpose that will presently appear.

To lock the running gear against rolling movement when left standing, lock fingers 20 are pivoted to one pair of radius rods 8 and arranged to turn between the spokes of the respective pair of wheels 10.

The body 21 of the improved folding baby carriage, as shown, is collapsible and preferably made of canvas, drilling or other suitable fabric. Suitable spreader rods are secured in the bottom and upper edge portion of the body 21 to hold the same in proper form. To each end of the body 21 is attached a strap 22 having at its outer end a ring 23 which detachably interlocks with one of the hooks 19. The length of the straps 22 is such that the rings 23 may be interlocked with the hooks 19 by springing the upper ends of the posts 6 slightly toward each other, and the body 21 and straps 22

form a tie between the posts 6 to firmly hold the same firmly against the couplings 7, and in turn, said couplings will be firmly held onto the reach 5, as shown in Fig. 1. 5 At one end of the body 21 is a folding hood 24, preferably made of the same material as the body 21 and secured over bows 25 which, at their ends, are pivoted on thumb-nut equipped trunnions 26 secured to 10 the body 21 and permit various different adjustments of the hood 24. A hood extension 27 connects the hood 24 to the body 21 and is secured thereto by overlapping engagement. To hold the body 21 against swinging movement or to limit the swinging movement, there is secured to opposite sides of the body 21 a buckle-equipped strap 28 secured at its intermediate portion to the reach 5. A buckle-equipped strap 29 is se-

cured to the upper edge portions 21 to hold 20 the baby or doll in the body 21.

What I claim is:

A folding running gear comprising a reach, a pair of posts, couplings foldably connecting the posts to the reach and having 25 sockets, a pair of radius rods having their inner ends telescoped into the sockets of each coupling and permanently secured therein, the outer end portions of each pair of radius rods being extended outward into axial 30 alignment to afford stub axles, and wheels journaled on the stub axles, said radius rods rigidly holding the wheels of each pair laterally spaced and for parallel movements to the reach during the movement of the running gear to and from folded positions. 35

In testimony whereof I affix my signature.

JULIUS A. MAHR.
